ERASER CLEANING MACHINE

Charles L. Gilbert, Spokane, Wash.

Application November 29, 1937, Serial No. 177,050

1 Claim. (Cl. 15—90)

The object of this invention is to provide a novel mechanism for cleaning black board erasers.

It is well known that these erasers are made of 5 porous felt which becomes permeated with chalk dust, and in the most improved erasers made up of abutting strips of felt, the chalk dust gathers between the strips, and in either case, the continued use of a chalk saturated eraser scatters 10 the dust in the atmosphere in a very unhealthy and objectionable manner.

It is a feature of this invention to subject the erasers to sustained agitation with the erasers bouncing against each other and impacting 15 against unyielding surfaces in an indiscriminate manner so that all portions thereof will be subjected to a dust releasing action.

It is also a feature of the invention to subject the erasers to a current of air, preferably generated by suction, so that any dust that has been 20 released by agitation, will not be permitted to again enter the erasers but will be carried away therefrom.

It is also an object of the invention to subject 25 the erasers, as a body, or in the aggregate, to a rotary motion in such a manner that centrifugal force will not be effective to prevent the erasers from falling and bouncing under substantial normal gravity action due to their weight.

It is also an object of that phase of the invention 30 in which the erasers are subjected to a revolving motion, to admit air radially outwardly from the axis of rotation and apply suction substantially coincident with and longitudinally 35 along the axis of rotation.

The invention has many other objects and features which will be more fully described in connection with the accompanying drawing and which will be more particularly pointed out in 40 and by the appended claim.

In the drawing:

Fig. 1 is a horizontal sectional view of one form 45 of my improved mechanism with parts thereof in elevation.

Fig. 2 is a sectional view on line 2—2 of Fig. 1, looking toward the left of that figure.

Fig. 3 is a sectional view on line 3—3 of Fig. 1, looking toward the right.

Fig. 4 is a plan view of a modern form of felt 50 eraser looking at the black board contacting surface thereof.

Fig. 5 is a sectional view thereof on an enlarged scale taken on line 5—5 of Fig. 4.

Like characters of reference designate similar 55

parts throughout the different figures of the drawing.

In the form shown, my improved agitator is in the form of a drum having a cylindrical portion 1, and a conical portion 2, formed of any suitable material such as sheet iron, for instance. The drum has a head 3, suitably secured thereto as at 4. A stub shaft is indicated at 5 and the same is secured to head 3 by having its flange 6 riveted thereto. A pedestal bearing comprising a pedestal 7 and bearing 8, serves to journal shaft 5, and form a rotatable support for one end of the drum. A suitable base 9, forms a convenient support for the machine, and the pedestal 7 is shown secured thereto at 10.

A bearing 11, having a pedestal 12, secured at 13, to base 9, forms the remaining rotary support for said drum. A suction shaft 14, which is tubular to form a dust passage 15, is journalled in bearing 11 and extends through the same toward 20 the fan suction means, to be later described. A suitable fitting is provided having a cylindrical section 16, secured to the exterior of shaft 14 and provided with a conical section 17, secured to the conical portion of said drum, as shown, and thereby serves to close that end of the drum. The intake end 18, of shaft 14, extends a short distance into the coned end of said drum to form a support for one end of an eraser abutment or impact member which additionally functions as a dust 30 egress means.

It will now be clear that shaft 14 is secured to the drum in a manner to form a rotative support therefor as well as to close the coned end thereof, and that the drum is effectively journalled in 35 bearings 8 and 11 for rotative movement.

Reference will next be made to the dust egress member and to the manner in which it is mounted.

As shown, said dust egress member is in the 40 form of a hollow screen 19, which is cylindrical in cross section although this particular cross section is not essential, and this member might be made of any type of foraminous material. I 45 employ a screen of sufficient guage of wire to be self stable and in practice, the screen successfully used has a mesh of one half inch openings. One end of the screen is shown mounted on the intake end of pipe 14 by being telescoped over it and clamped by a ring 20. The remaining end is socketed in a flange 21 formed integral with a disc 22, the latter being secured to head 3. Thus it will be seen that this impact member 19 is not only 50 axially disposed in the drum but that it also ro- 55

tates with the drum, this latter being also an important feature.

The head 3, is provided with one or more air ingress openings 23 which are disposed radially outwardly from the axially disposed air egress. Inside the drum is a plurality of eraser lifters which may comprise strips of angle iron each having one flange 24, projecting radially inwardly of the drum and the remaining flange 25, secured 5 to the drum, as shown. These lifters successively lift and then release the erasers, as will be subsequently described. An opening 26, in the drum is shown closed by a lid 27 that is hinged at 28, and provided with a screw clamp 29, at its free 10 end whereby the drum may be opened to insert and withdraw the erasers. On the periphery of the drum I have shown a pulley 30 about which a belt 31 may be trained, the belt being driven by any suitable source of power, not shown, to rotate 15 the drum.

Reference will next be made to the manner and means for initiating a current of air through the agitating drum.

A suction fan is provided having a fan casing, 25 the periphery of which is indicated at 32 and the sides at 33 and 34. The egress end 35, of pipe 14, opens to the suction side of the fan casing through side wall 33, and to insure a dust proof engagement, a sleeve 36 surrounds pipe 14 between bearing 11 and the side wall 33 and is 30 suitably flanged for effective engagement with said parts and may be secured to side wall 33, as shown. Brackets 37 and 38, secured to walls 33 and 34, and to base 9, serve to support the fan 35 casing, and a bearing 39 forms a part of bracket 38 to journal a fan shaft 40, which extends through wall 34 and carries a fan 41, having a hub 42, mounted on fan shaft 40. As a source of power, an electric motor 43, mounted on a 40 pedestal 44, secured to base 9, may be directly connected to the fan shaft 40. The fan casing has a discharge outlet pipe 45 to which may be attached at 46, any suitable kind of porous bag 47, for collecting the dust and releasing the air, 45 the bag 47 being inflated when the machine is in operation, as indicated in Fig. 1.

The coned end 2, of the drum 1, affords an additional drum area without unduly enlarging the cylindrical portion thereof, which has the 50 advantage of increasing the air volume for carrying off the chalk dust. This is due to the fact that the cone is at the discharge end of the drum. Further, the cone is really an extension of the drum, as far as interior area is concerned, 55 and I am thus able to locate the outlet opening 18 endwise away from the cylindrical portion of the drum thereby permitting use of a longer abutment tube 19, which serves to increase the air egressing capacity thereof. It will also be clear 60 that the wall of the cone serves to converge the air currents toward the outlet 18, and prevents the formation of objectionable air eddies.

In Figs. 4 and 5, I have shown a modern eraser having a felt back 49, and a series of laterally 65 abutting strips of felt 50, which are usually glued to the felt back 49, but are free from engagement with each other. As the eraser is used on a black board, the strips 50 separate from each other to an extent sufficient to admit chalk dust 70 between them, and thus it will be seen that it is not only the dust with which the felt becomes permeated or saturated, that is of importance, but also the dust between the strips 50 that must be removed. It is also important to note that the 75 felt from which these erasers are made, is suffi-

ciently porous to admit of saturation of chalk dust.

The operation of my improved method and machine may be clear from the foregoing but I will briefly recapitulate the same as follows:

The lid 27 is opened and the drum is charged with erasers, and in my present machine, I can clean three hundred and fifty erasers in one operation. The drum is proportioned for a relatively large capacity to avoid frequent cleaning operations and I obtain the best results when there is a very marked congestion of erasers in the drum but not enough to prevent the erasers from individually descending separately after they have been released, by the lifters.

After the drum has been charged, the lid is closed and power is applied to belt 31 to rotate the drum. In practice, I have found that a speed of about forty revolutions per minute is an effective speed, and this rate of speed is important to 20 a successful operation because centrifugal force does not and should not function since if it did, these light weight erasers would be impelled to cling to the inner face of the drum. Therefore a speed of rotation wherein centrifugal force is not 25 effective, is a primary requisite. This applies, not only to the erasers but also to effective egress of the dust laden air since the latter is egressed axially of the drum and hence centrifugal action would rather retard than promote such discharge. 30

As the drum revolves, the lifters 24 successively pick up and elevate the erasers and then drop or release them and they not only fall against each other but also against the screen, and when they impact against the screen 19, their course is deflected and changed because said screen rotates 35 with the drum.

I have successfully generated suction with the fan revolving at one thousand seven hundred and fifty revolutions per minute and it will be seen 40 that the fan will draw air in through the radially outer ingress openings 23, in head 3, and therefore these streams of incoming air will mingle with the tumbling erasers that are descending, and also those in any peripheral relation to the impact member 19, and an important feature is 45 that because the openings 23 revolve with the drum, there is a most effective changing relation of the air intake as well as a constantly changing position of the erasers. It will also be clear that 50 these tumbling erasers will continually obstruct and divert currents of dust laden air and cause them to take circuitous paths of travel.

The dust laden air is drawn through the screen impact member 19 at any longitudinal 55 point in the drum as the screen provides an elongated egress air passage whose interior is unobstructed by the tumbling and bouncing erasers, and this is its value in addition to acting as an impact member. It may also be stated that the 60 screen 19, performs no function as a screen, as there is nothing to separate, since all the dust laden air passes out through pipe 14. However, I have found in practice, that by extending the screen as shown, I greatly hasten the cleaning 65 operation.

The coned end of the drum, and the holes 43, prevent dust laden air accumulations and also cause disruption of any air eddies. The dust laden air passes out through pipe 14 and is admitted centrally of the fan casing from which it is peripherally discharged at 45, into a collecting bag 47, of sufficiently porous material to discharge the air and retain the dust. I have successfully cleaned a charge of erasers in thirty 70 75

minutes with the machine I now have in operation, which machine embodies all the features set forth herein.

It will now be clear that I do not rely wholly upon suction or agitation alone, but on both. The agitation brings the dust to the surface, and of course in so doing, actually releases some of it, and the suction carries off the released dust and also extracts the surface dust from the erasers. 0 The speed of the fan is of course regulated so that suction is not sufficient to drag the bouncing erasers toward or into the coned end of the drum as that would interfere with a free falling action initiated by the lifters. Hence, suction is 5 only strong enough to draw out the dust laden air.

It is believed that my improved machine will be fully understood from the foregoing description, and while I have herein shown and described one 10 specific form of the invention, I do not wish to be limited thereto except for such limitations as the claim may import.

I claim:

In an eraser cleaner, a rotatively driven drum 25 having a cylindrical section adapted to contain erasers sufficient in number substantially to

amount to congestion and provided with a conical section forming an extension of the interior of said cylindrical section and said conical section having an outlet opening and the remaining end of said cylindrical section having air intake openings, suction means connected with said outlet opening for sustaining currents of air through said drum to carry off dust laden air therefrom, said cylindrical section having lifters for lifting and then releasing the erasers to tumble 10 the latter whereby the tumbling erasers will continually obstruct and divert currents of dust laden air from their normal courses, and a tubular abutment connected with said conical section and discharging into said outlet opening 15 and extending through said conical section and axially through said cylindrical section and being secured thereto to rotate therewith and form a revolving abutment to arrest and deflect erasers descending thereagainst, said abutment being 20 foraminous substantially throughout its length to form an elongated egress for entrance thereinto of obstructed currents of dust laden air at any point lengthwise of said drum.

25

CHARLES L. GILBERT.
